US0D1022789S

(12) **United States Design Patent** (10) Patent No.: **US D1,022,789 S**
(45) Date of Patent: ** Apr. 16, 2024

(54) **BELT LOOP**
(71) Applicant: **Vista Outdoor Operations LLC**,
Anoka, MN (US)
(72) Inventors: **Paul N. Smith**, Bozeman, MT (US);
Troy E. Lance, Livingston, MT (US);
Oscar C. Woods, Manhattan, MT (US);
Daniel D. Sereday, Belgrade, MT (US);
Christopher J. Michael, Belgrade, MT
(US)
(73) Assignee: **Vista Outdoor Operations LLC**,
Anoka, MN (US)
(**) Term: **15 Years**
(21) Appl. No.: **29/721,548**
(22) Filed: **Jan. 21, 2020**

Related U.S. Application Data

(63) Continuation of application No. 16/364,141, filed on Mar. 25, 2019, now Pat. No. 10,619,974, which is a continuation of application No. 29/647,062, filed on May 9, 2018, now Pat. No. Des. 860,641.

CLAIM

The ornamental design for a belt loop, as shown and described.

DESCRIPTION

FIG. 1 is a rear, top perspective view of a belt loop in accordance with our new design;

FIG. 2 is a front, bottom perspective view thereof;

FIG. 3 is a front, top perspective view thereof;

FIG. 4 is a rear, bottom perspective view thereof;

FIG. 5 is a rear view thereof;

FIG. 6 is a front view thereof;

FIG. 7 is a right side view thereof;

FIG. 8 is a left side view thereof;

FIG. 9 is a top view thereof; and,

FIG. 10 is a bottom view thereof.

1 Claim, 8 Drawing Sheets
